UNITED STATES PATENT OFFICE.

GUSTAV BUCKY, OF NEW YORK, N. Y.

X-RAY TUBE.

Application filed September 22, 1925, Serial No. 57,820. Renewed January 14, 1928.

It is well-known that ordinary glass opposes a substantial resistance to the passage of X-rays, so that only relatively hard rays will become available exteriorly of the tube 5 in which the X-rays are produced, unless provision is made for inserting a window of a material which offers less resistance to the passage of X-rays than ordinary glass. For this purpose, so-called Lindemann glass 10 has been used with considerable success. This material, however, has the drawback that so far only comparatively small windows of it could be fitted into an X-ray tube, such windows being at most slightly less 15 than one inch square. This reduces the area of the pencil of X-rays emitted through the window. As it is highly desirable in many cases to obtain a more powerful emission of X-rays, I have devised a way permitting 20 windows of Lindemann glass or similar material to be made of considerably larger size than hitherto. According to my present invention, the window is constructed with a reinforcing skeleton of platinum wire or 25 equivalent support. The preferred way of making the window consists in first placing the wire net in the opening of the tube, then anchoring the edges of the window to the glass wall by melting the latter to embed 30 the outer portions of the net therein, and finally applying the Lindemann glass to the wire support, so that the meshes of the net will be filled by the Lindemann glass. I am thus enabled to make the Lindemann glass 35 windows as large as desired, and to obtain a radiation field of much greater area than has been possible hitherto. It is true that theoretically the shadow cast by the wires will cut down slightly the emission of X-rays, but this is practically negligible, since 40 the apparent loss is more than compensated by the very substantial increase in the size of the radiation field.

A satisfactory and preferred embodiment 45 of my invention is illustrated by the accompanying drawings, in which Fig. 1 is an elevation of an X-ray tube having a window constructed according to my invention, and Fig. 2 is a cross section on line 2—2 of 50 Fig. 1.

In the body 10 of the evacuated bulb are located the cathode 11 and the anticathode 12, of any well-known or approved construction. Said body has an opening in the edge 55 13 of which is embedded the marginal por-

tion of a wire netting 14 made of platinum or other suitable metal. This wire netting has its meshes filled by a mass or pane 15 of Lindemann glass or similar material permeable even to relatively soft X-rays, 60 and preferably the wire netting lies entirely within the Lindemann glass, that is, no part of the netting is exposed either on the outside of the tube or on the inside thereof. Strong windows of practically any size desired 65 may be constructed after this fashion in the wall of X-ray tubes.

As mentioned hereinabove, the preferred way of applying the improved window consists in first placing the wire net in the opening of the tube while the edges of the opening are softened by heat, thus causing the marginal portion of the netting 14 to become embedded and anchored in the edge 13 of the opening. Then the Lindemann glass 70 is applied in a molten or at least viscid condition so that it will adhere both to the netting 14 and to the edge 13 of the opening, thus sealing the latter and forming the plate or pane 15. While this pane has been shown 75 plane, I desire it to be understood that this is not essential, and that various modifications may be made without departing from the nature of my invention as defined in the claims. 80

I claim:

1. An X-ray tube having a body with an opening, a wire netting, the marginal portion of which is anchored in said opening, and a pane of material readily pervious to 90 X-rays, supported on said netting and fused to the edge of said opening.

2. An X-ray tube having a body with an opening, an apertured support, the marginal portion of which is anchored in said opening, and a pane of material readily pervious to 95 X-rays, carried by said support and sealing said opening.

3. An X-ray tube having a body with an opening, an apertured support, the marginal 100 portion of which is anchored in said opening, and a pane of material readily pervious to X-rays, carried by said support and sealing said opening, said support being embedded in its entirety within the edge of the 105 body opening and within the said pane.

In testimony whereof I hereunto set my hand.

GUSTAV BUCKY.
